UNITED STATES PATENT OFFICE.

ARTHUR J. HARTLEY, OF PEORIA, ILLINOIS, ASSIGNOR TO HART GRAIN WEIGHER CO., OF PEORIA, ILLINOIS, A CORPORATION OF ILLINOIS.

FOLDING-CONVEYER SUPPORT.

Application filed June 10, 1922. Serial No. 567,320.

To all whom it may concern:

Be it known that I, ARTHUR J. HARTLEY, a citizen of the United States of America, residing at Peoria, in the county of Peoria 5 and State of Illinois, have invented certain new and useful Improvements in Folding Conveyer Supports, of which the following is a specification.

My invention relates to conveyers adapted to be used in connection with threshing 10 machines.

The invention has special reference to a folding conveyer, comprising a receiving and delivery section, adapted specially for 15 use in connection with feeders for threshing machines.

My invention is specially directed to a support for a conveyer, when extended, including a relationing of parts, that, 20 through extension of the latter, relative interlocked adjustiment of members of the support will cause the conveyer to be maintained in the desired supported and extended position, but operable, through mere 25 depression of the outer end of the receiving section of the conveyer, to relieve the interlocked supporting relationship mentioned, to permit the conveyer sections to be folded 30 together and to be supported in an elevated position.

The invention also includes detailed structural parts, relative fashioning and arrangement of the same and combination of parts 35 hereinafter more particularly indicated.

In the drawings, Figure 1, is a side elevation, showing the forward portion of a threshing machine and a conveyer in extended and folded positions.

Figure 2, is a detailed plan view of the 40 supporting member for a conveyer.

Figure 3, is a side elevation showing the same subject matter as that disclosed in Figure 2.

Figure 4, is an end view showing the same 45 structural subject matter as disclosed in Figures 2 and 3.

Figure 5, is a detailed view of portions of the conveyer sections, showing in solid lines said sections extended, and in dotted lines, a relative folding of the same.

Figure 6, is a sectional view on the line 50 $a-a$ of Figure 5.

Figure 7, is a detailed plan view of a modified form of a support for a conveyer and 55 the manner of relationing the same thereto.

Figure 8, is a detailed side elevation showing the same subject matter as shown in Figure 7.

Figure 9, is an end view showing the same subject matter of disclosure as that in Figures 7 and 8 and,

Figure 10, is a side elevation, also showing the modified structure disclosed in Figure 2, with an extended showing of the structure and relationship of parts over that of 65 said Figure 2.

Both prior patents and the practical art disclose sectional conveyers, adapted to be supported in a manner to permit relative extension of the sections comprising said 70 conveyer, and to permit folding of the same in position to be conveniently carried in connection with a threshing machine. Also the prior art mentioned, discloses conveyer supports comprising a reach or bar member, 75 pivotally connected to framing members of a threshing machine and also, connected in a pivotal manner with a supplementary framing attached to said conveyer section, such pivoting to the supplementary 80 framing portion, being in off-centered relationship to the hinged center of the conveyer sections, and including a relationing of said parts, that, when the conveyer is extended, the supporting members will be 85 relatively positioned to form an interlock, effective to stop and hold the conveyer in a desired normal workable position and including a breaking of the locked relation of the supporting parts by mere depression 90 of the rearward end of the receiving section, whereby said sections may be folded together. I am not, however, aware of any structure being employed to attain the results mentioned, that includes the combination of parts here presented, which gains the 95 result of greater simplicity and cheapness of structure, as well as the very material result of being able to fold the sections into substantially contact relation, as distinguished from the necessary spaced relationship of parts that results from the employment, as indicated in the prior patent and practical art, of a supplementary framing applied to and extending from the receiving section to which the supporting bar member is attached.

In the drawings A, refers generally to standard threshing machine parts and B, to framing members of a frame work, includ- 110

ing similar and connected parts on the opposite side of the machine, which will hereinafter be referred to as a frame 9. 10, refers generally to a conveyer, comprising receiving sections 11 and 12, hinged together by means of the link 13, its opposed end being pivotally connected respectively as at 14 and 15, with the receiving and delivery sections of the conveyer. The forward end of 10 the conveyer is pivotally connected with the thresher body as at 16. 17, is a bracket extended from the rear end of the conveyer, there being a similar bracket on the opposite side, and 18 refers generally to framing connection therebetween. 19, shows a conventional draper or carrier element, suitably supported upon and driven from, related sprocket members.

Our preferred form of support for the 20 conveyer includes reach members 20 and 21, pivoted respectively, member 20 to frame B, as at 22, and member 21, to the receiving section of the conveyer as at 23, said reach members being pivoted together as at 24, in 25 off-centered relationship to the pivoting center 14, of the link 13, with the delivery section 12, of the conveyer. Reach member 21, is provided with the rearwardly extending and integrally connected stop member 25, 30 which lies normally in contact relation with the lower body portion of receiving section 11. The relationship of the supporting member, comprising reach members 20 and 21, with the frame and receiving section 11, 35 is such, that their combined length is slightly greater than that of the distance between pivot points 22 and 23 thereof respectively, with the frame 9 and section 11, when the conveyer sections are extended so 40 that, as a practical result of such relationing, when the sections are so extended, the weight of the reach members causes the pivot point 24, therebetween, to lie slightly below a line drawn through the centers of pivots 22 and 23, thereby, in conjunction with the 45 stop member 25, effecting an interlocked support for the conveyer in its normal working position.

When it is desired to fold the conveyer for 50 convenience in transportation the interlocked position of the supporting members for the conveyer may be broken by merely applying pressure downward upon transverse framing member 18, at the outer extremity of receiving section 11, thereby effecting a turning of the section upon its pivotal center, which causes stop member 25, to be depressed with a corresponding elevation 55 of attached reach member 21, which causes the pivoting center of the connected reach members to be raised to a point above a line through the centers of pivots 22 and 23, thereby relieving the interlock between 60 said members and permitting the sections to be turned upon the pivoting centers 14 and

15, to a folded relationship and to be manually forced into the position shown in dotted lines in Figure 1. When the sections are so folded together, they are designed to be supported, in the dotted line position shown, 70 through and by means of hook members 26, on reach members 20 (there being provided similar reach members 20 and 21, and stop member 25, on the opposite side of the conveyer,) engaging a cross framing member as 75 at 27.

I have shown in Figures 7, 8, 9 and 10, a modified form of the conveyer supporting structure, wherein reach members 20^a and 21^b, are in the same form and for the same 80 relationship to a frame member and the receiving section of a conveyer, except that the stop member 25, shown in the preferred form, hereinbefore described, is omitted and a special hooked stop member 25^a is provided, having connection directly with the receiving section 11^a and adapted, through its hooked portion, to form a supporting seat for reach member 21^b, when the conveyer sections are extended and the reach members are in locked supporting position.

So far as simplicity of structure and operative result are concerned, the two structures are quite similar and it is not thought necessary to further enlarge upon the modified 95 structure description.

What I claim is:

1. In a device of the class described, in combination, a frame support, a conveyer pivoted thereto, comprising delivery and receiving sections hinged together, a support comprising reach members, their outer ends pivoted respectively to the frame and the receiving conveyer sections, and their inner ends pivoted together in off-centered relationship with respect to the hinged center of the conveyer sections, including a relationing of the support to the frame and conveyer, that, when the latter is extended the pivoting center of the reach members of the support will lie below a plane through the centers of the pivotal connection of the support with the frame and receiving conveyer section, and means for holding the reach members in such off-centered relation when 115 the conveyer sections are extended, including a relationing of said holding means to the receiving conveyer section, that, depressing movement of the latter will relieve the interlocked relation between the support and the conveyer, whereby the latter may be folded into carrying position in connection with the frame.

2. In a device of the class described, in combination, a frame support, a conveyer 125 pivoted thereto, comprising delivery and receiving sections hinged together, a support comprising reach members hingedly related, its opposed ends pivoted respectively to the frame and the receiving conveyer sections, 130

and means for maintaining the reach members in off-centered relationship, when the conveyer sections are extended, including a relationing of said means to the receiving section and a member of the support, whereby folding movement imparted to the receiving section, will relieve the interlocked supporting relation of the supporting member, to permit continued folding action of the section

3 In a device of the class described, in combination, a main frame, a conveyer frame hinged to the main frame, comprising delivery and receiving sections hinged together, a supporting member, its ends connected respectively with the frame and the receiving conveyer section, comprising reach portions pivoted together in off-centered relation with respect to the hinged center of the connected conveyer sections, and means, including the relationing of the supporting member to the frame and conveyer, for maintaining the members of the support in offset relation, with respect to end pivoting

centers, when said conveyer sections are extended, said means, also, including the capability of adjusting said reach members through physical depressing action applied to the outer end of the delivery section of the conveyer, whereby the sections may be folded together

4. In a device of the class described, in combination, a main frame, a conveyer frame hinged to the main frame, comprising delivery and receiving sections hinged together, a support comprising pivoted reach members, its opposed ends connected respectively with the frame and the receiving section of the conveyer, and means for maintaining the supporting member in off-centered relationship when the conveyer sections are extended, but co-acting with the receiving section, through depressing movement thereof, to relieve the reach members from interlocked extended supporting relation, to permit folding action of the conveyer sections.

In testimony whereof I affix my signature.
ARTHUR J. HARTLEY.
